UNITED STATES PATENT OFFICE

LAVERN A. SEGER, OF GRAND RAPIDS, MICHIGAN, ASSIGNOR OF ONE-HALF TO
FREDERICK W. KRAMER, OF GRAND RAPIDS, MICHIGAN

PISTON FOR INTERNAL COMBUSTION ENGINES

Application filed May 4, 1931. Serial No. 534,911.

The object of this invention is an improvement in the construction and design of a piston which will dispense with the use of specially constructed oil control rings now widely used for controlling the surplus oil in internal combustion engines.

By this construction it is possible to have all ring grooves in the piston of uniform width or of any width now in use. It is not necessary to have the lower ring groove wider than the upper grooves to accommodate a specially constructed oil control ring. Additional benefits accruing from this construction are lower first cost, lower maintenance cost, better control of surplus oil, and less liability of clogging the rings. A cooler running piston head results, due to the more complete ventilation of the lower ring land.

Objects pertaining to details will definitely appear from the description to follow.

A preferred embodiment of my invention is illustrated in the accompanying drawing, in which:

Fig. 1 is a detail view of the piston partially in section on a line corresponding to line 1-1 of Fig. 2.

Fig. 2 is a detail transverse sectional view through the piston with the rings removed, taken on line 2-2 of Fig. 1, showing the oil drainage means.

Fig. 3 is an enlarged detail sectional view on line 3-3 of Fig. 4, the section corresponding to the section of Fig. 1.

Fig. 4 is an enlarged detail elevation view of a portion of the cylinder corresponding to that illustrated in Fig. 3.

The parts will be identified by their numerals of reference which are the same in all the views.

1 is the broken section of an engine cylinder. 2 is the piston, 21 is the skirt of the piston, 22 are the ring grooves, 23 is the lower land, 24, 24 are the intermediate lands, and 25 is the top land of the piston adjacent and between the piston grooves.

3, 3 are the usual construction of piston ring, four rings being illustrated in this behalf. The number may be varied, but four are preferred. The land 23 is specially formed by having milled in its lower surfaces 50 curved notches 231 which notches extend to and cut into the bottom of the ring groove and across the bottom thereof to a slight extent, as indicated in Fig. 2. Centrally of each curved notch 231 a radial hole 232 leads 55 into the hollow piston for the passage of oil. These are what I call by-pass openings.

The skirt 21 has the usual fit with the interior of the cylinder. Inasmuch as all piston lands are relieved—thereby being smaller in diameter than the remainder of the piston—in order to take care of the expansion of the heat, I form in the piston land between the two lower rings a compensating reservoir 60 extending around the piston for the collection of surplus oil. This surplus oil is collected in the notches 231 and is discharged within the hollow of the piston through the apertures 232, thereby avoiding the discharge 65 of the surplus oil into the combustion chamber 70 of the motor.

My improved by-pass piston makes possible the better control of surplus oil through the channel formed around the lower ring land, by simply relieving the same. The 75 checked by-passes formed directly below the lower ring land and above the lower ring groove connecting with the same, the lower ring forms the check and acts as a scraper. The second ring acts both as scraper and 80 compression. What is meant by "check" is that oil that passes over the lower ring and through the by-passes finds its way back of the lower ring and cannot return to the cylinder wall.

The lower ring is not a compression ring because of the by-passes. This ring acts as a scraper, check and deflector. What is meant by "deflector" is that pressure or "blow-by" that occurs is checked by this ring, 85 90

thus preventing oil being blown off the skirt of the piston. At the same time deflecting this blow-by through the by-passes greatly assists in returning surplus oil to the original source of supply.

As complicated as this may seem, it really is simple. There is a series of slots at regular intervals around the lower edge of the lower ring land cutting into and across the lower ring grooves with drilled holes through the piston wall. This feature secures all the advantages of the very best oil rings now in use, such as the continuous groove for collection and distribution of oil to the returns, without any of the disadvantages found in oil rings, such as breakage, clogging, etc. This feature in itself prevents clogging. The difficulties of oil piston rings are avoided.

By this means it will be observed that ordinary piston rings are used, these being far more economical than any specially designed oil control rings. The drainage passages for the oil are not subjected to wear and will last indefinitely. These passages can be made of a size to control any oil condition in any type of internal combustion engine.

I have illustrated the same proportioned for average conditions. The structure I have illustrated with the milled slots accomplishes the drainage without materially lessening the strength of the piston and are very readily formed by a milling tool. Other forms might be made use of, but the advantages of the particular form are apparent.

I desire to claim the invention specifically as illustrated and also broadly as pointed out in the appended claims.

Having thus described my invention, what I claim as new and desire to secure by Letters Patent is:

1. A piston having the usual skirt and ring grooves with lands therebetween, the land next succeeding the skirt being formed with notches facing the skirt and extending to the bottom and across the bottom of the ring groove, the said groove being provided with perforations at the bottom of the notches for the by-pass and delivery of the lubricating oil into the body of the piston.

2. A piston having the usual skirt and ring grooves with lands therebetween, the land next succeeding the skirt being formed with notches facing the skirt and extending to the bottom of the ring groove, the said groove being provided with perforations at the bottom for the by-pass and delivery of the lubricating oil into the body of the piston.

3. A piston having the usual skirt and ring grooves with lands therebetween, the land next to the oil ring groove being formed with notches facing the skirt and extending to the bottom and across the bottom of the ring groove, the said groove being provided with perforations at the bottom of the notches for

the by-pass and delivery of the lubricating oil into the body of the piston.

4. A piston having the usual skirt and ring grooves with lands therebetween, the land next to the oil ring groove being formed with notches facing the skirt and extending to the bottom of the ring groove, the said groove being provided with perforations at the bottom for the by-pass and delivery of the lubricating oil into the body of the piston.

In witness whereof I have hereunto set my hand.

LAVERN A. SEGER.
